CLAIM

The ornamental design for a display screen with a transitional graphical user interface, as shown and described.

DESCRIPTION

FIG. 1 is a front view of a first image in a sequence for a display screen with a transitional graphical user interface;

FIG. 2 is a front view of a second image thereof;

FIG. 3 is a front view of a third image thereof;

FIG. 4 is a front view of a fourth image thereof; and

FIG. 5 is a front view of a fifth image thereof.

FIG. 6 is a front view of a sixth image thereof.

FIG. 7 is a front view of a seventh image thereof.

FIG. 8 is a front view of a eighth image thereof.

FIG. 9 is a front view of a ninth image thereof.

FIG. 10 is a supplemental view of FIG. 1, shown with the broken lines illustrating portions of the graphical user interface removed for clarity of illustrating the claimed design.

FIG. 11 is a supplemental view of FIG. 2, shown with the broken lines illustrating portions of the graphical user interface removed for clarity of illustrating the claimed design.

FIG. 12 is a supplemental view of FIG. 3, shown with the broken lines illustrating portions of the graphical user interface removed for clarity of illustrating the claimed design.

FIG. 13 is a supplemental view of FIG. 4, shown with the broken lines illustrating portions of the graphical user interface removed for clarity of illustrating the claimed design.

FIG. 14 is a supplemental view of FIG. 5, shown with the broken lines illustrating portions of the graphical user interface removed for clarity of illustrating the claimed design.

FIG. 15 is a supplemental view of FIG. 6, shown with the broken lines illustrating portions of the graphical user interface removed for clarity of illustrating the claimed design.

(Continued)

FIG. 16 is a supplemental view of FIG. 7, shown with the broken lines illustrating portions of the graphical user interface removed for clarity of illustrating the claimed design. FIG. 17 is a supplemental view of FIG. 8, shown with the broken lines illustrating portions of the graphical user interface removed for clarity of illustrating the claimed design; and,

FIG. 18 is a supplemental view of FIG. 9, shown with the broken lines illustrating portions of the graphical user interface removed for clarity of illustrating the claimed design. The outermost broken line rectangles illustrate a display screen and forms no part of the claimed design. The broken lines of text, numbers, icons, and boxes illustrating portions of a graphical user interface form no part of the claimed design. The areas filled in with dotted shading illustrate contrasting appearance, and form a part of the claimed design. The areas filled in with fill lines illustrate an additional contrasting appearance of a background fill, and form a part of the claimed design. Shapes are filled in with particular shading to indicate a contrast in appearance and form a part of the claimed design.

The appearance of the image sequentially transitions between images shown in FIGS. 1 through 9. The process or period in which one image changes to another forms no part of the claimed design.
